UNITED STATES PATENT OFFICE.

FRENCH E. RANSDELL AND HENRY C. MUDDIMAN, OF MANASSAS, VIRGINIA.

DOOR CATCH AND BUFFER.

SPECIFICATION forming part of Letters Patent No. 708,401, dated September 2, 1902.

Application filed April 3, 1902. Serial No. 101,188. (No model.)

To all whom it may concern:

Be it known that we, FRENCH E. RANSDELL and HENRY C. MUDDIMAN, citizens of the United States, residing at Manassas, in the 5 county of Prince William and State of Virginia, have invented certain new and useful Improvements in Door Catches and Buffers; and we do declare the following to be a full, clear, and exact description of the invention, 10 such as will enable others skilled in the art to which it appertains to make and use the same, reference being had to the accompanying drawings, and to the letters of reference marked thereon, which form a part of this 15 specification.

This invention relates to devices of the class mentioned which are attachable to a door jamb or casing; and its objects are to prevent noise and jarring when the door is being closed and to avoid rattling of the door after it is closed.

The accompanying drawings illustrate the invention, in which—

Figure 1 is an elevation of part of a door-jamb and our device in normal position thereon; Fig. 2, a plan view in normal position; Fig. 3, a plan with the door, fragmentarily shown, closed against it; Fig. 4, a rear elevation; Fig. 5, a section on line xx of Fig. 4; 30 and Fig. 6, a plan similar to Fig. 3, but with the sides of the outer and inner frames partly broken away.

Like letters of reference denote corresponding parts in the several views.

The letter A indicates the outer frame of the device, having a back A^2 and two sides A^3 , a part of the latter being bent outwardly at a right angle to form wings $a a$, which are provided with nail or screw holes $a' a'$. B is 35 an inner frame secured to the outer frame by a pivot b and having a limited movement thereon. It has no back corresponding to the part A^2 of the outer frame, but its two sides B' are connected to the frame's angular 40 portion, which forms the contact-faces $e e'$. The plan outlines of these two frames nearly 45 correspond, except that the angle A' of the outer frame is approximately a right angle, while the angle of the inner frame is less than 50 that of the outer frame. A spring C, preferably a leaf-spring fixed in the outer frame,

operates to keep the inner frame in normal position by pressure against the back of the face e . When the door is closed, the contact-face e of the inner frame is forced back 55 by the door. The inner frame is turned on the pivot b , and the other face e' is pressed against the edge of the door, which is thus securely held. On opening the door the spring C throws the inner frame into normal 60 position again, which is thus securely held. The use of rubber cushions D either on the faces $e e'$ or on the door enhances measurably the effect of the device.

It is evident that our device may be attached to the door-casing over the door and that a block or other projection secured on the door may engage its faces instead of the door itself and with the same results.

We do not limit ourselves to the exact 70 forms of the frames and spring shown in the drawings, but may make a reasonable variation therefrom without departing from the spirit of the invention.

What we claim, and desire to secure, is— 75

1. A door catch and buffer comprising an outer frame having a back and two sides, an inner frame having an angular front and two sides, and pivoted in said outer frame, a contact-face on said inner frame to yieldingly 80 receive the impact of the closing door, another face to engage the edge of the door when closed, and means to restore the inner frame to its normal position when released from the door-pressure. 85

2. A door catch and buffer having an outer frame provided with attaching-wings and screw-holes therein, and having a back and two sides, an inner frame having two sides and pivotal connection with said outer frame, 90 and contact-faces disposed at an angle to each other, a spring to hold the inner frame in normal position and a cushion interposed between the door and said faces substantially as herein specified. 95

In testimony whereof we affix our signatures in presence of two witnesses.

FRENCH E. RANSDELL.
HENRY C. MUDDIMAN.
